US00D777442S

(12) **United States Design Patent** (10) **Patent No.:** **US D777,442 S**
White et al. (45) **Date of Patent:** **** Jan. 31, 2017**

(54) **ELECTROLYTIC BRUSH**(71) Applicant: **Ensitech IP Pty Limited**, Emu Plains (AU)(72) Inventors: **Clive Stuart White**, Faulconbridge (AU); **Mark Robert Fischer**, Cabramatta (AU); **Franco Fornesari**, Springwood (AU)(73) Assignee: **ENSITECH IP PTY LIMITED** (AU)(**) Term: **14 Years**(21) Appl. No.: **29/508,800**(22) Filed: **Nov. 11, 2014**(30) **Foreign Application Priority Data**

May 12, 2014 (AU) 12270/2014

(51) **LOC (10) Cl.** ..... **04-02**(52) **U.S. Cl.**USPC ..... **D4/100**; D4/199(58) **Field of Classification Search**

Primary Examiner — Susan Moon Lee(74) *Attorney, Agent, or Firm* — Galgano IP Law PLLC; Thomas M. Galgano; Jessica G. McDonald(57) **CLAIM**

The ornamental design for an electrolytic brush, as shown and described.

DESCRIPTION

FIG. 1 is a front perspective view of the electrolytic brush showing the design;

(Continued)

FIG. 2 is a rear perspective view; and,
FIG. 3 is a side view thereof, other side views are identical.

1 Claim, 3 Drawing Sheets
